(57) **CLAIM**

The ornamental design for a cake decorating tool, as shown and described.

DESCRIPTION

FIG. 1 is a front perspective view of a first embodiment of a cake decorating tool, showing my new design.

FIG. 2 is a front perspective view thereof, with the lid shown separately for ease of illustration.

FIG. 3 is a top plan view thereof.

FIG. 4 is a front elevation view thereof.

FIG. 5 is a side elevation view thereof.

FIG. 6 is a bottom plan view thereof.

FIG. 7 is a front perspective view of a second embodiment of the cake decorating tool.

FIG. 8 is a top plan view thereof, with the lid shown separately for ease of illustration.

FIG. 9 is a front elevation view thereof.

FIG. 10 is a side elevation view thereof.

FIG. 11 is a front perspective view thereof.

FIG. 12 is an exploded front perspective view of a third embodiment of the cake decorating tool.

FIG. 13 is a side elevation view thereof, with the lid shown separately for ease of illustration.

FIG. 14 is a bottom plan view thereof.

FIG. 15 is an exploded front perspective view of a fourth embodiment of the cake decorating tool.

FIG. 16 is a side elevation view thereof, with the lid shown separately for ease of illustration; and,

FIG. 17 is a bottom plan view thereof.

The broken lines show portions of the cake decorating tool that form no part of the claimed design.

1 Claim, 12 Drawing Sheets
